CIRCUIT INTERRUPTER

Howard W. Graybill, Honey Brook, Pa., assignor
to Westinghouse Electric Corporation, East
Pittsburgh, Pa., a corporation of Pennsylvania

Application November 23, 1945, Serial No. 630,430

10 Claims. (Cl. 175—294)

1

This invention relates generally to electric circuit interrupters, and particularly to devices for protecting a circuit against overloads and surges.

One object of this invention is to provide a novel structure which is adapted to automatically open an electric circuit in response to the presence in the circuit of excessive currents.

Another object of this invention is to provide an electric circuit opening device with novel latch release means for a movable contact member which is biased to move to open the circuit when released.

Another object of this invention is to provide a circuit protective device having means responsive to excess currents for switching the circuit to ground; with novel means for extinguishing the arc drawn during such switching operation.

Another object of this invention is to provide a circuit protective device which is automatically operative to ground the circuit in response to excess currents, with surge protective means which cooperates therewith to extinguish the arc drawn when the device operates in response to excess currents.

These and other objects of this invention will become more apparent on consideration of the following detailed description of a preferred embodiment thereof and the attached drawing, in which:

Figure 1 is a side elevational view of a device embodying this invention;

Fig. 2 is a front view of the circuit protective device illustrated in Fig. 1; and

Fig. 3 is an enlarged sectional view of the interrupter contact structure of the device shown in Figs. 1 and 2.

The circuit protective device illustrated on the drawing is adapted to be mounted on a single insulator 2 which is elongated in form with a reduced central portion for receiving a mounting bracket 3 secured thereon as by a clamping bolt 5. The ends of insulator 2 are also reduced in section for receiving terminal brackets 4 and 6, respectively, adapted to be secured thereon as by clamping bolts 8. Although a single insulator mounting is illustrated, it will be obvious to those skilled in the art that terminal brackets 4 and 6 may be mounted on separate insulators, if desired.

Upper terminal bracket 4 has secured thereto an angular contact bracket 10, for example, as by bolts 12. Contact bracket 10 has a forwardly extending contact arm 14 with an elongated centrally located narrow slot 16 extending inwardly from the outer end thereof. A casing 18, pref-

2

erably of a molded insulating material, such as a synthetic resin, having an open bottom and a peripheral flange around the lower edge thereof is adapted to be secured to contact arm 14 as by bolts 19 extending through the contact arm and bottom flange of the casing. At the forward end of casing 18 there is provided a substantially U-shaped terminal rod 21, with one leg 20 being threaded and extending through an aperture in the top of casing 18 and secured relative to the casing by nuts 22 and 23. A pair of nuts 22 is provided at the top of the casing for securing one conductor of the circuit to terminal rod 21. Within casing 18, leg 20 of terminal rod 21 extends through an aperture in a bimetal element 24, which may be secured in adjusted position on the rod as by nuts 26. The bight portion 30 of the terminal rod extends through a notch 28 formed in the forward lower edge of casing 18, and leg 32 of the terminal rod extends upwardly in front of the casing, and has an angularly directed outer arcing horn portion 34, for a purpose to be described. An angular arc bracket 36 may be secured to leg 32 of terminal rod 21 as by a securing plate 38 secured to bracket 36 as by bolts 40, with leg 32 of the terminal rod held therebetween. Arcing bracket 36 has a rearwardly extending part 42 secured to the lower flange of housing 18 as by bolts 44, and it terminates short of the forward end of contact arm 14 to leave a space 46 therebetween.

Bimetal element 24 is formed in the usual manner of a pair of laminations 47 and 49 secured together in intimate relation, as by welding or the like, with the lamination 47 being of a metal such as steel having a relatively low coefficient of thermal expansion, whereas lamination 49 is of a metal such as brass having a relatively high coefficient of thermal expansion. It will be observed, therefore, that when bimetal element 24 is heated, the outer end will deflect upwardly as viewed in Fig. 3. The outer end of bimetal element 24 has an abutment 48 secured thereto as by a rivet 50, and the outer end of the bimetal element is electrically connected with contact arm 14 of bracket 10 by a flexible conductor 52 soldered or otherwise secured at its ends to contact arm 14 and bimetal element 24, respectively. Abutment 48 on the bimetal element is adapted to cooperate with one end of a latch lever 54 which is pivotally mounted intermediate its ends on contact arm 14 as at 56. A light coil tension spring 58 has one end hooked in an opening provided in latch lever 54, and the other end hooked over an anchor lug 60 secured to the contact arm 14 to bias the

latch lever to a position slightly clockwise from that shown in Fig. 3, so that the upper end of the lever will normally be in a position to be engaged by abutment 48 of the bimetal element.

The lower end of latch lever 54 is adapted, at the closed circuit position, to be engaged by a contact arcing tip 62 secured to the outer end of a switch member 64 which is pivotally mounted at its other end on terminal bracket 6, as at 71. Switch member 64 is preferably of a resilient conducting material, and in the device illustrated in the drawing comprises a pair of resilient rods 66 and 68 having the inner ends thereof bent towards each other to enter openings in opposite sides of terminal bracket 6 to be pivotally mounted at 71, and a coil spring 69 reacts between extension 70 of rod 68 and bolt 8 to bias switch member 64 in a clockwise direction, as viewed in Fig. 1, to open circuit position. Rod 68 of the switch member has the inner extension 70 adapted to limit circuit opening movement of the switch member by engagement with the lower end of insulator 2 after predetermined opening movement. The outer ends of rods 66 and 68 of switch member 64 are each bent to form a loop 72 at substantially the same position so that the loops 72 form a hookeye for receiving a hookstick operating member, for operation of switch member 64 in a manner to be described. It will be observed that rods 66 and 68 of switch member 64 are substantially U-shaped in profile, so that in the closed circuit position contact tip 62, which is secured across the outer ends of rods 66 and 68 as by welding or the like, engages contact arm 14 under pressure due to the fact that the ends of the switch member are stressed toward each other a certain amount, and for this purpose loops 72 act to increase the flexibility of the switch arm.

To provide surge protection and to extinguish arcs drawn during circuit opening movement of switch member 64, there is provided a rod 74 of electrical conducting material having its inner end mounted on an extension 76 of mounting bracket 3, for example, as by being threaded and secured to extension 76 by nuts 78 (only one of which is shown). Rod 74 includes a forwardly extending portion 80, at the end of which is an angularly bent upright portion 82 which extends upwardly to the region of terminal bracket 4 and then a transversely extending part 84 extends to a point in opposition to arcing bracket 36, and the rod terminates in an angularly extending arcing horn part 86 which diverges with respect to arcing horn 32. Substantially at the bend 85 between parts 84 and 86 of rod 74, the rod lies closest to arcing bracket 36 so that these two members form electrodes for a surge gap.

Arcing horn 86 is grounded, for example, as by grounding supporting bracket 3 as illustrated in Fig. 1, and it will be observed that the normal current flow through the device illustrated at the closed circuit position thereof is from terminal rod 21 through bimetal element 24, flexible conductor 52, contact arm 14, contact tip 62, through switch member 64 to terminal bracket 6 and a terminal 88 secured thereto. When currents above a predetermined value flow through this circuit, bimetal element 24 will be heated, and the outer end will deflect upwardly to release the upper end of latch lever 54. When latch lever 54 is released from abutment 48, it can then be rotated counterclockwise by switch member 64 under the influence of its biasing spring 69, and the switch member can move to open circuit po-

sition. As soon as contact tip 62 goes past the lower end of latch lever 54, the latch lever will be returned to a position slightly clockwise from the position shown in Fig. 3 by return spring 58.

As contact tip 62 slides over the lower surface of contact arm 14 and onto the lower surface of arm 42 of the arcing bracket, the bimetal element is shunted out of the circuit because the circuit then proceeds from terminal rod 21 through arcing bracket 36, contact tip 62 and switch member 64 to the lower terminal 88. As contact tip 62 continues to move to the right, as viewed in Figs. 1 and 2, it will leave arcing bracket 36, and an arc will be drawn between tip 62 and the arcing bracket, and as soon as contact tip 62 passes immediately under electrode portion 85 of the grounded rod 74, the arc will be transferred from arcing tip 62 to rod 74, where it will be subjected to the arc extinguishing action of horns 32 and 86, namely, the arc will be elongated by travel upwardly on the horns and by looping outwardly, due to the magnetic forces present. Travel of switch member 64 is stopped just beyond electrode portion 85, as illustrated by the partial dotted line position shown at Fig. 1, by engagement of extension 70 with the lower end of insulator 2, as previously described. Currents of appreciable value may be extinguished upon automatic opening of the device, as described above, due to the arc extinguishing action of arc horns 32 and 86. However, it may be desirable where extremely heavy short-circuit currents are encountered to provide a circuit breaker or the like connected in the same circuit, to open the circuit on such heavy short-circuit currents in case the arc extinguishing action of the arcing horns is insufficient to extinguish such currents.

After an automatic circuit opening operation as described above, the interrupter may be closed by inserting a hookstick, or other operating member, in hookeyes 72 and moving switch member 64 in a counterclockwise direction from the dotted line position shown in Fig. 1 back toward the full line position. The circuit is reestablished when arcing tip 62 engages arcing bracket 36, and such engagement causes the outer end of switch member 64 to be bent downward to stress the switch member, and thus cause the arcing tip to engage part 42 of the arcing bracket under pressure, and finally to engage contact arm 14 in a similar manner, and eventually the arcing tip engages latch lever 54 rotating it in a clockwise direction while passing by, and when the latch lever is restored by its spring 58, the contact tip will engage the other side of the latch lever and hold it in engagement with abutment 48 on the bimetal element. The circuit may be opened manually, if desired, by inserting a hookstick or the like in hookeyes 72 and pulling downwardly to spring the outer end of switch member 64 downwardly below the lower end of latch lever 52, after which the switch member may be rotated in clockwise direction to its open position either manually, or by its biasing spring 69.

The gap between arc horns 32 and 86 should be adjusted to coordinate with the insulation of the apparatus, such as a transformer or the like, which is being protected, so that surge voltages above the safe value of such insulation will break down the gap, to form an arc on the arc horns which will be extinguished in the manner described above. If the power follow current is of exceptionally high value, or if this apparatus is to be mounted below other conductors or ground-

ed parts, it may be desirable to depend upon a reclosing circuit breaker, or the like, connected in the circuit for interrupting the circuit to extinguish such arc. However, the arc extinguishing ability of arcing horns 32 and 86 will operate to extinguish overload currents of substantial value.

From the foregoing it is believed apparent that this invention provides a novel electric circuit protective device capable of protecting the circuit and apparatus therein from overloads and surges, and that by a novel cooperation of parts, arcs due to both surges and overloads are caused to form between the same pair of electrodes, and are subjected to the same arc extinguishing action. There is also disclosed herein a circuit protective device having a novel switch member construction, together with novel latch means, for normally holding the switch member closed and adapted to be automatically released in response to overloads, and when released, to short-circuit the overload responsive means in a novel manner.

Having described a preferred embodiment of the invention in accordance with the patent statutes, it is to be understood that this invention is not to be limited to this particular structure inasmuch as it will be obvious to persons skilled in this art that many changes and modifications may be made therein without departing from the broad spirit and scope of this invention. For example, it has already been pointed out that instead of having a single insulator mounting that spaced insulators may be used, and these may be mounted on a channel support or the like which is grounded and also supports arcing horn rod 80. Accordingly, it is desired that this invention be interpreted as broadly as possible, and that it be restricted only as required by the prior art.

I claim as my invention:

1. A circuit protective device, comprising, separable line contacts one of which is mounted for movement into and out of engagement with the other, grounded terminal means having a terminal portion supported adjacent to but spaced from said other contact to form a low resistance surge gap to ground and which is of a length correlated to protect the circuit insulation, and said gap extending adjacent to and in the direction of movement of said movable contact so that the arc drawn upon separating movement of said movable contact will transfer to the terminals of said surge gap.

2. A circuit protective device, comprising, separable line contacts one of which is mounted for movement into and out of engagement with the other, grounded terminal means having a terminal portion supported adjacent to but spaced from said other contact to form a low resistance surge gap to ground and which is of a length correlated to protect the circuit insulation, and means to transfer the arc drawn during circuit opening movement of said movable contact to the terminals of said surge gap.

3. A circuit protective device, comprising, separable line contacts one of which is mounted for movement into and out of engagement with the other, grounded terminal means having a terminal portion supported adjacent to but spaced from said other contact to form a low resistance surge gap to ground and which is of a length correlated to protect the circuit insulation, means to transfer the arc drawn during circuit opening movement of said movable contact to the terminals of said surge gap, and means for extinguishing an arc formed across said gap.

4. A circuit protective device, comprising, separable line contacts one of which is mounted for movement into and out of engagement with the other, grounded terminal means having a terminal portion supported adjacent to but spaced from said other contact to form a low resistance surge gap to ground and which is of a length correlated to protect the circuit insulation, said gap extending adjacent to and in the direction of movement of said movable contact so that the arc drawn upon separating movement of said movable contact will be transferred to the terminals of said surge gap, and means for extinguishing an arc formed across said gap.

5. A circuit protective device, comprising, separable line contacts one of which is mounted for movement into and out of engagement with the other, a line terminal electrically connected with each of said contacts, latch means for normally holding said movable contact in engagement with said other contact including means in the connection of said other contact and its terminal which is responsive to a predetermined condition of the circuit to release said latch means, a stationary arcing electrode independently connected with the terminal of said other contact and positioned adjacent the path of circuit opening movement of said movable contact, a ground electrode spaced from said arcing electrode to form a low resistance surge gap to ground and which is of a length correlated to protect the circuit insulation, and said gap extending adjacent to and in the direction of movement of said movable contact so that the arc drawn upon separating movement of said movable contact will be transferred to the terminals of said surge gap.

6. A circuit protective device, comprising, separable line contacts one of which is mounted for movement into and out of engagement with the other, a line terminal electrically connected with each of said contacts, latch means for normally holding said movable contact in engagement with said other contact including means in the connection of said other contact and its terminal which is responsive to a predetermined condition of the circuit to release said latch means, a stationary arcing electrode independently connected with the terminal of said other contact and positioned adjacent the path of circuit opening movement of said movable contact, a ground electrode spaced from said arcing electrode to form a low resistance surge gap to ground and which is of a length correlated to protect the circuit insulation, said gap extending adjacent to and in the direction of movement of said movable contact so that the arc drawn upon separating movement of said movable contact will be transferred to the terminals of said surge gap, and means for extinguishing an arc formed across said gap.

7. A circuit protective device, comprising, separable line contacts one of which is mounted for movement into and out of engagement with the other, spaced electrodes one of which is grounded and the other of which is electrically connected to one of said contacts to form a low resistance surge gap to ground and which is of a length correlated to protect the circuit insulation, and said gap extending adjacent to and in the direction of movement of said movable contact so that the arc drawn upon separating movement of said movable contact will be transferred to the terminals of said surge gap.

8. A circuit protective device, comprising, separable line contacts one of which is mounted for pivotal movement into and out of engagement

with the other, a line terminal electrically connected with each of said contacts, latch means for normally holding said movable contact in engagement with said other contact including means in the connection of said other contact and its terminal which is responsive to a predetermined condition of the circuit to release said latch means, a stationary arcing electrode independently connected with the terminal of said other contact and positioned adjacent the path of circuit opening movement of said movable contact, a ground electrode spaced from said arcing electrode to form a low resistance surge gap to ground and which is of a length correlated to protect the circuit insulation, said gap extending adjacent to and in the direction of movement of said movable contact so that the arc drawn upon separating movement of said movable contact will be transferred to the terminals of said surge gap, and said movable line contact being of resilient material bent so as to engage the other line contact and arcing electrode under pressure.

9. A circuit protective device, comprising, separable line contacts one of which is mounted for movement into and out of engagement with the other, a line terminal electrically connected with each of said contacts, electro-responsive means for causing separation of said contacts and connected in the circuit between said other contact and its terminal, a stationary arcing electrode independently connected with the terminal of said other contact and positioned adjacent the path of circuit opening movement of said movable contact, a ground electrode spaced from said arcing electrode to form a low resistance surge gap to ground and which is of a length correlated to protect the circuit insulation, and said gap extending adjacent to and in the direction of movement of said movable contact so that the

arc drawn upon separating movement of said movable contact will be transferred to the terminals of said surge gap.

10. A circuit protective device, comprising, an elongated supporting insulator, line terminals mounted on said insulator adjacent opposite ends thereof, supporting means mounted on said insulator at an intermediate point for supporting said device on a grounded structure, relatively stationary and movable contacts mounted on said terminals, respectively, for relative movement into and out of engagement to open and close the circuit between said terminals, and a ground electrode mounted on said supporting means and extending to a position spaced from the stationary contact a distance to form a low resistance surge gap to ground and which is of a length correlated to protect the circuit insulation, and said gap extending adjacent to and in the direction of movement of said movable contact so that the arc drawn upon separating movement of said movable contact will be transferred to the terminals of said surge gap.
